UNITED STATES PATENT OFFICE.

OSCAR H. WOLNER, OF ELCOR, MINNESOTA.

SERIAL-FLOW TURBINE.

Application filed May 31, 1922. Serial No. 564,758.

To all whom it may concern:

Be it known that I, OSCAR HERBERT WOLNER, a citizen of the United States of America, and a resident of Elcor, in the county of St. Louis and State of Minnesota, U. S. A., have invented certain new and useful Improvements in Serial-Flow Turbines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to serial flow turbines, and consists in providing means whereby the steam is admitted at a plurality of points about the periphery of the turbine casing through controlled nozzles. The steam from each nozzle acts on the rotor blades a plurality of times, and is divided each time into two lateral streams by a central rib on the rotor and then exhausts laterally to two exhaust chambers, one on each side of the blading and is conducted to a common discharge.

The turbine may operate in conjunction with a condenser or not, as desired.

The steam distribution is such that the turbine starts with great facility and the separately controlled steam nozzles enable utilization of the steam variable in accordance with a wide range of power requirements.

Referring to the drawings, which illustrate my invention, and in which like parts are similarly designated—

Figure 1 is an enlarged partial longitudinal section through a steam supply nozzle and the adjacent blades.

Fig. 2 is a section on line 2—2, Fig. 1.

Fig. 3 is an end view, partly in section, and

Fig. 4 is a longitudinal section through the entire turbine.

I have chosen to illustrate my invention in connection with a turbine of the disc type having a central rotor disc 6, Fig. 3,

secured by bolts 7 or otherwise between flanges 8 of two aligned shafts 9 and 10. These shafts are mounted in pedestals 11 and 12 on a base 13.

The rotor 6 has a hub or annular flange 55 14 that fits against the inner edges of the two lateral dished cover members 15 and 16. Annular external ribs 17 near the center of these members provide sufficient metal for the holding bolts 18 for securing 60 packing glands 19.

At the periphery these covers 15 and 16 (which are somewhat dished) are wider apart than at their center, and secured between them is the annular steam distributing member 20, having a middle peripheral live steam channel 21 and two lateral peripheral exhaust channels 22 that terminate or discharge into the exhaust pipe union 23.

The live steam pipe union 24, Fig. 4, is shown located in a horizontal position, but may be located at any other point of the periphery to suit the conditions existing at the plant where it is to be used.

There are also provided supports 25 for the turbine that are bolted to the base 13.

Around the steam distributing member are steam valves 26 controlling steam supply nozzles 27. The valves 26 are tapered 80 and have screw-threaded portions 28 of at least as great a diameter as the valves, so that each individual valve may be readily removed without removing the bushing 29, shown in enlarged view, Figs. 1 and 2.

The rotor 6 has a central rib 30 between lateral flanges 31 forming two continuous grooves 32 having rounded bottoms, the outer sides of the grooves being decidedly inclined to the central vertical plane through the rib to facilitate the exit of steam.

The rotor is slotted from side to side and inserted in these slots are the flat plate turbine blades 33 which with their rounded shanks 34 are slightly tapered for a proper 95 driving fit.

The guide blades 35 are similarly made. In the middle member 20 the dividing portion 36 has inwardly projecting flanges 37 in which some of the guide blades are fitted 100.

and between which are formed expansion chambers 38 to permit the steam to pass from one side of the blade around the shank to the other side of the blade.

6. Immediately back of each nozzle 27 between a pair of guide blades 35 is formed an exhaust chamber 39 that has lateral discharge openings 40, Fig. 2, to the exhaust channels 22, and behind each exhaust chamber

10 39 are two expansion chambers 38, which arrangement prevails between each two successive steam supply nozzles 27, the object being to cause the steam from the steam nozzles 27 to act directly on the rotor 15 blades 33, and as these pass the stationary guide blades 35 to expand it a plurality of times in pockets 38 and cause the steam after each expansion to act again on the rotor blades, finally exhausting just behind 20 the next inlet nozzle 27.

The operation is as follows:

Live steam is admitted to the turbine through inlet union 24 and fills the steam channel 21. The cone valves 26 are gradually opened and steam passes through the nozzles 27 and impinges on the rotor blades 33, being divided into two streams by the rib 30. As the rotor moves past the stationary guide blades 35 steam from the 30 pocket formed between two successive rotor blades issues in two streams between the next successive guide blades 35 into the first expansion chamber 38, passes around the root of blade 37 therein to the opposite 35 side blade and is directed again against the rotor blades, this operation, in the present instance, is repeated in the following expansion chamber 38, and the steam finally leaves the rotor through exhaust chamber 39 and 40 passages 40 in a divided stream to the two exhaust channels 22 to the exhaust pipe at 23.

The steam in passing from between a moving pair of rotor blades while expanding in an expansion chamber is of course augmented by steam from the next following blade.

Any leakage at the joint between the rotor and stator passes into lateral chambers 41 between the rotor disc 6 and the casing members 15 and 16 producing a counter pressure, while radiation of heat from the live steam channel 21 is guarded against by arranging it between the exhaust channels 22.

The bevelled ends of the stator blades 35 are somewhat wider than the bevelled ends of the rotor blades 33, so that there will be a period of time when there will not be a 60 continuous open passage from an inlet nozzle 27 to the exhaust.

I claim—

1. In a serial flow turbine, a bladed stator having a peripheral steam channel and a peripheral exhaust channel at each side

thereof, a bladed rotor, nozzles admitting steam from said steam channel to the rotor blades, means in the plane of the wheel to permit expansion of the motive fluid a plurality of times between successive channels, 70 and means to permit the steam to exhaust laterally and simultaneously into both exhaust channels at points behind the respective nozzles.

2. In a serial flow turbine, a bladed stator having a peripheral live steam channel, a peripheral exhaust channel at each side thereof, a plurality of inlet nozzles supplied from said live steam channel, expansion chambers between successive nozzles in the 80 rotor plane, a bladed rotor having a mid-rib forming a pair of buckets between each two succeeding blades, said pair of buckets not exceeding the width of said nozzles and expansion chambers, there being lateral 85 exhaust ports in said stator to exhaust chambers behind each nozzle.

3. In a serial flow turbine, a bladed stator having live steam and exhaust channels, a plurality of angularly spaced, valve-controlled steam inlet nozzles to admit steam from said live steam channel, an expansion chamber between successive nozzles, an exhaust chamber back of each nozzle and a bladed rotor having a rib dividing the steam 95 into lateral streams to said expansion chamber and exhaust.

4. In a serial flow turbine, a stator having a middle member having a peripheral steam channel, and flat blades arranged in transverse slots in said stator and extending from side to side thereof, steam inlet nozzles to admit steam between a pair of blades, a plurality of expansion chambers between successive nozzles, an exhaust chamber behind 105 each nozzle and peripheral exhaust channels flanking the steam channel, each exhaust chamber having ports leading to both of said exhaust channels.

5. In a serial flow turbine, the combination with a bladed rotor disc having a central flange, dished covers spaced from said disc and forming leakage chambers, and a packing gland between said flange and covers.

6. In a serial flow turbine, a stator transversely slotted, a rotor transversely slotted, and laterally removable flat transversely tapered plate blades having enlarged shanks and seated in the slots of said stator and 120 rotor.

7. In a serial flow turbine, an annular steam distributing member having a middle steam channel and a continuous exhaust channel on each side of said steam channel, steam nozzles supplied from said channel, a bladed rotor having a mid rib forming pairs of buckets between each two succeeding blades, dished covers secured to said member and between which said rotor 125 130

turns, and packing means between the rotor and covers.

8. In a serial flow turbine, a bladed peripheral steam distributing member, dished covers secured to said member, a bladed rotor disc mounted between said covers, a continuous steam channel and a lateral continuous exhaust channel on each side of said steam channel.

16

In testimony that I claim the foregoing as my invention, I have signed my name hereto.

OSCAR M. WOLNER.
